UNITED STATES PATENT OFFICE.

ROBERT J. WHITE, OF WILKINSBURG, PENNSYLVANIA, ASSIGNOR TO WESTINGHOUSE ELECTRIC & MANUFACTURING COMPANY, A CORPORATION OF PENNSYLVANIA.

MACHINE FOR BANDING ARMATURES.

Application filed September 16, 1922. Serial No. 588,681.

To all whom it may concern:

Be it known that I, ROBERT J. WHITE, a citizen of the United States, and a resident of Wilkinsburg, in the county of Allegheny and State of Pennsylvania, have invented a new and useful Improvement in Machines for Banding Armatures, of which the following is a specification.

My invention relates to tension devices, 10 more especially to a device for banding armatures of electrical machines with steel wire.

It is among the objects of this invention to provide a device of the above-designated 15 character which shall be of simple compact structure, which shall be easy to manipulate and which shall be adjustable to obtain various degrees of tension on the wire drawn therethrough.

20 In the accompanying drawing constituting a part hereof and in which like reference numerals designate like parts,

Figure 1 is a side elevational view of a 25 device embodying the principles of this invention; and

Fig. 2 is an end view thereof.

Referring to the Fig. 1, the reference numeral 1 designates a pair of end supports or pillar blocks to which a bed plate 2 is secured. The bed plate 2 is provided with an accurately machined way 3 on which a head stock 4 having a movable center 5 is mounted, and the bed plate is further provided with a side opening 6 in which a saddle 7 is movably mounted. The armature to be wound is rotatably mounted on the center 5 of the head stock and a similar center of the tail stock (not shown) and is rotated by a suitable source of motor power, such 40 as a motive, belt transmission, or the like.

The saddle 7 is provided with a hand wheel 8 having a pinion mounted on its supporting shaft 9 which engages a gear rack in the bed plate 2 to effect lateral movement 45 of the saddle within the limits of the opening 6. A bearing bracket 10, adapted to rotatably mount a shaft 11, is secured to the saddle 7 in alignment with a similar bracket 12. A tension drum 13 is rotatably mounted 50 on the shaft 11 in alignment with a plurality of wire guide wheels 14 and a pair of guide wheels 15, the latter being rotatably mounted on movable centers 16 having a

helical spring 17 disposed therebetween and being secured in a guide bracket 18 mounted on the saddle 7. A plurality of bearing brackets 19, 20 and 21, adapted to receive a plurality of gear shafts 22 and 23, respectively, parallel with the shaft 11, are likewise secured to the saddle 7 and are provided with a plurality of gears 24, 25 and 26 constituting a gear transmission. 55

A motor 27 is mounted on one end of the saddle and is connected by a pinion 28 to the gear 26. 60

The wire supply reel (not shown) is rotatably mounted between the supporting pillar 1 of the bed plate, and the banding wire 29 is connected from the reel over a wire-guide wheel 30 through the guide 70 wheels 14, thence to the tension drum 13 on which it is wound, thence to the yieldingly mounted guide wheels 15, from which it is conducted to the armature.

My apparatus operates briefly as follows: 75 The banding wire 29 is secured to the armature 31, as is graphically shown in the Fig. 2, and an initial tension is applied to the wire through the motor 27, which is a constant-torque motor energized to function opposite to the direction of rotation of the armature. The motor functions similarly to a motor employed in gathering reels where the cable is unwound against the torque of the motor, so as to prevent slack. 80 The amount of tension may be varied by changing the ratio of the gears 12 and 25 which is accomplished by shifting a lock pin 32 to engage any one of the gears 24 with the shaft 11. 85

In starting the winding of the wire 29 around the armature 31, an excessive tension or strain is produced which is temporarily taken up by the yielding guide wheels 15 until compensated for through the feeding mechanism. The tension may be varied at any time by manipulating the pin 32 to mesh a gear corresponding to the tension desired. The wire is wound on the armature, and the saddle or carriage 7 may be fed along as the wire forms in contiguous layers on the armature by manipulating the hand wheels 8 in the direction in which the wire is wound. 95

100 From the above it is evident that my device is capable of banding armatures at a

uniform tension and with a specific amount of tension in a simple and expedient manner.

Although I have described a specific embodiment of my invention, it will be obvious to those skilled in the art that various modifications may be made in the details of construction without departing from the principles herein set forth. For instance, the 10 general construction of the bed-plate support and carriage mounting may be modified to suit any specific application, and the various parts of my apparatus may be altered to accomplish the purpose for which it is 15 utilized.

I claim as my invention:

1. A wire-tension device comprising a gear transmission, a tension drum and an actuating device, said drum and actuating device 20 being connected to said transmission.
2. A wire-tension device comprising a gear transmission, a tension drum and an electric motor, said drum and motor being connected to said transmission.
- 25 3. A wire-tension device comprising a gear transmission, a tension drum and a motor connected to said transmission and means for changing the gear ratio of said transmission.
- 30 4. A wire-tension device comprising a gear transmission, a tension drum and a motor connected to said transmission and means for changing the gear ratio of said transmission and the tension on said drum.
- 35 5. A wire-tension device comprising a gear transmission, a tension drum and a constant-torque motor, said drum and motor being connected to said transmission means for changing the gear ratio of said 40 transmission and the tension on said drum.
- 45 6. A wire-tension device comprising a gear transmission, a tension drum and constant-torque motor connected to said transmission and means for varying the tension

on said drum, said means comprising a shifting pin for locking one of the gears to the tension-drum axle.

7. A wire-tension device comprising a gear transmission, a tension drum and a constant-torque motor connected to said 50 transmission, said motor being energized to apply torque in a direction opposite to the normal rotation of said drum, and means for varying the gear ratio of said transmission.

8. A wire-tension device comprising a bed plate, a carriage movably mounted thereon, a tension drum, a gear transmission and a constant-torque motor mounted on said carriage, a plurality of wire-guide wheels 60 rotatably mounted in co-operative alignment with said drum on said carriage and means for rotatably mounting an armature on said bed plate to be wound.

9. A wire-tension device comprising a bed plate, a carriage movably mounted thereon, a tension drum, a gear transmission and a constant-torque motor mounted on said carriage, a plurality of wire-guide wheels 65 rotatably mounted in co-operative alignment with said drum, and means for relieving the initial tension of the wire.

10. A wire-tension device comprising a bed plate, a carriage movably mounted thereon, a tension drum, a gear transmission and a constant-torque motor mounted on said carriage, a plurality of wire guide wheels rotatably mounted in co-operative alignment with said drum and means for relieving the initial tension of the wire, said 70 means comprising a pair of wire-guide wheels rotatably mounted on a pair of movable centers having a coil spring disposed therebetween.

In testimony whereof, I have hereunto 85 subscribed my name this 12th day of September, 1922.

ROBERT J. WHITE.
